ERROR DETECTING DEVICE FOR PRINTING
TELEGRAPH RECEIVERSJames A. Spencer, Teaneck, N. J., assignor to
Radio Corporation of America, a corporation of
Delaware

Application June 10, 1937, Serial No. 147,398

7 Claims. (Cl. 178—69)

This invention relates to error detecting devices and has particularly to do with the provision of means for detecting errors of transmission of code signals for printing telegraph apparatus. Printing telegraph code signals are especially susceptible to distortion and to mutilation when transmitted by radio channels. It is, therefore, an object of my invention to provide means for detecting instances of mutilation of code signals and to provide means either for preventing the receiving teletypewriter from printing characters erroneously or by enabling such a printer to indicate the reception of a mutilated signal by means of a special error indicating type impression on the record to be transcribed.

In carrying out my invention I prefer to make use of a signalling code having equal intervals for each character and having preferably seven or eight time intervals allotted to each code signal so that a fixed number of marking time intervals may be maintained independently of the character designation for each code signal. A code signalling system in which the signals are of equal length and possess a fixed ratio other than 1 to 1 between the number of marking and spacing units thereof has been disclosed in a pending application, Serial No. 78,348, filed May 7, 1936, by John B. Moore, et al., and assigned to the assignee of the instant application.

A telegraph printer adapted to be actuated by code signals of uniform length and having as many as seven or eight time elements in each code signal would require, of course, an equal number of selector bars. As explained in the application of Moore, et al. above referred to, it is desirable that a fixed number of selector bars be actuated in making the selection of any character to be printed. If a shift key is employed, then seven units in the code signal would be sufficient. If no shift key is employed, then eight units would be required for differently characterizing each code signal for ordinary communications purposes. My invention has particularly to do with a novel means for counting the number of marking impulses in each code signal so that if the fixed number of such impulses is three, then the reception of any code signal having more or less than three marking impulses would be effective upon the error detecting device of my invention so as to enable the receiving printer to print an error indicating character in place of the intended character.

I have found that an electrical circuit arrangement for carrying out the objects of my invention is preferable to a purely mechanical struc-

ture which might be designed for obtaining similar results. If the marking impulses are mechanically counted, it is true that it is possible to detect the errors which may occur in transmission, but an objection to the use of mechanical means lies in the problems of maintenance of such a system as well as problems of maintaining a suitable printing speed. My invention is free from these objections because it operates on the basis of current differentials resulting from the completion of a definite number of circuits, each completion being upon reception of a marking impulse. The error detector, therefore, operates under the direct control of the received signal.

My invention will now be described in more detail, reference being made to the accompanying drawing, the sole figure of which shows a circuit diagram of apparatus for attaining the objects of the invention.

The drawing shows a receiving relay 15 responsive to incoming signals. The tongue of this relay vibrates between contact points 16 and 17 fed respectively with positive and negative potential from a local direct current source. As the commutator brush 18 moves over the selector segments 1 to 7 inclusive marking or spacing impulses will be applied to the selector bar operating magnets 8 to 14 inclusive. If desired, a receiving printer may be employed which does not require a separate selector bar actuating magnet 80 for each selector bar. In such case magnets 8 to 14 inclusive may be understood as constituting a bank of storage relays.

Each of the magnets 8 to 14 inclusive has associated therewith a pair of locking contacts 19 and an additional pair of make contacts 20. One contact of the latter pair is connected to a direct current source. The other contact of this pair leads to one or another of the several resistors R₁ to R₇ inclusive and thence over a common conductor through the winding of a relay 21. This relay is adjusted to pull up its armature when any three of the relays 8 to 14 inclusive have been actuated thereby to feed current through at least three of the resistors R₁—R₇.

Another relay 22 is in circuit with the relay 21 but is adjusted to operate upon a strength resulting from the completion of more circuits in the resistance network R₁—R₇ than there are normal marking elements in a code signal.

Still another relay 23 is in series with the relays 21 and 22 and is adjusted to operate on a current value derived from the completion of one or more circuits in the resistance network R₁—R₇.

The series circuit through the relays 21, 22 and 23

- 23 leads eventually back to the direct current source and, say, the negative side thereof which, for the sake of simplicity in the description to follow, will be assumed to be grounded. The armature 24 of relay 23 is also grounded and when drawn up to its front contact 25 puts ground potential on one side of an operating magnet 26. The other side of the winding of magnet 26 leads to the armature of relay 22. The back contact 10 of relay 22 is connected to the armature of relay 21. The back contact of relay 21 and the front contact of relay 22 are both fed with positive potential through a resistor 27. The system is so designed that the operating magnet 26 may be 15 energized upon the reception of a mutilated signal having either more or less than the standard number of marking impulses. When the magnet 26 is energized its armature is pulled up and clears a path for type lever 29 to drop into a slot 20 in the code bar assembly 30. From this point the printing function is identical with a normally selected character. The type face associated with the special lever 29, however, is of special design indicating an error.
- 25 The mode of operation of the system in case of reception of a mutilated signal having more than the proper number of marking impulses is as follows:
- Each of the relays 21, 22 and 23 is actuated. 30 Positive potential from the direct current source is, therefore, conducted through resistor 27, the front contact of the relay 22, the winding of magnet 26, the front contact of relay 23, and thence through its armature 24 to ground.
- 35 In case of reception of a mutilated signal having less than the proper number of marking impulses the operation is as follows:
- Relay 23 alone will be energized because there is not sufficient current passing through one or 40 two of the resistors R₁-R₇ to enable relays 21 and 22 to respond. However, current is fed from the positive side of the potential source through resistor 27, the back contact and armature of relay 21, the back contact and armature of relay 45 22, and thence to the winding of magnet 26 on the other side of which is the connection to the front contact 25 of the now energized relay 23 whose armature 24 completes this circuit to ground.
- 50 When the correct number of marking impulses has been received for the printing of a character of the message, relays 21 and 23 will be actuated but relay 22 will remain unenergized. In this case there will be no complete circuit from the positive 55 side of the local source through the magnet 26 because the armature of relay 21 is not against its back contact and the armature of relay 22 is not against its front contact. Hence no error indication will be made if the number of marking impulses in the received code signal is normal.
- The locking circuits associated with the relays 8 to 14 inclusive are opened at the end of each printing cycle by means of a contact 31 operated by the printing bale of the printer. This printing bale is not shown because it is well known in printing apparatus of conventional types.
- It will be well understood by those skilled in the art that I may, if desired, operate contacts similar to those shown in association with the 70 relays 8-14 merely by applying such contacts to the printer code bars. In this manner it will be possible to eliminate the relays 8-14 and their associated locking circuits.
- Since it can be seen that the relay 23 is always 75 actuated upon the receipt of one or more marking

impulses in the code signal, it would be possible to insert the winding of relay 23 into the common conductor at the point designated 32, if desired.

Other modifications of my invention will possibly occur to those skilled in the art, but yet they are to be understood as comprehended within the scope of the claims.

I claim:

1. In a printing telegraph receiving system, a printer, selective means for causing said printer to print a character in response to the reception of a single unmutilated multi-element code signal, a plurality of code-element responsive devices, code element impulse counting means comprising a plurality of parallel impedance circuits each respectively closable by one of said responsive devices, and means including a plurality of error-detecting relays operable under control of currents through said impedance circuits, said currents being established upon reception of a single mutilated code signal for causing an error-indicating character to be printed in place of the character intended to be selected by the first said means. 25

2. In a printing telegraph receiving system, a printer having character selecting means responsive to a fixed number of marking elements of a uniform-length code signal, means for detecting instances of mutilation of the received signals, said means comprising a relay operable upon receipt of one or more marking impulses in a single one of said code signals, a second relay operable upon receipt of at least the normal number of marking impulses in said code signal, and a third relay operable only upon receipt of a superfluous marking impulse in said code signal, and means to print an error-indicating character in response to the cooperation of said relays when operated upon receipt of an abnormal number of marking 40 impulses. 30

3. A printing telegraph apparatus having a plurality of de-coding members each actuatable in response to the reception of a marking element of a code signal, type selecting elements each selectable upon the actuation of a fixed and uniformly normal number of said de-coding members, and means for indicating instances of mutilation of a code signal, said means comprising an electro-magnetic type-selecting element, a plurality of relays differentially biased, thereby to respond to currents of respectively different amplitudes, said relays being cooperatively actuatable to energize the last said type-selecting element upon reception of an abnormal number of marking impulses in the time interval allotted to a single code signal, and a plurality of impedance circuits each closable respectively upon the actuation of one of said de-coding members, said circuits being connected in parallel with one another and in series with all of said relays thereby to control the number of said relays to be actuated in dependence upon the amplitude of the current traversing said relays, which amplitude is a function of the number of marking elements 60 of the received signal. 50

4. In a telegraph system, code signal receiving apparatus, a receiving printer having character-selecting elements, means including a plurality of de-coding members operable in response to 70 unrepeated signals for controlling the actuation of said character-selecting elements, an impedance circuit appropriate to and closable upon the actuation of each selected de-coding member, all of the impedance circuits being parallel con- 75

5 nected, a relay system in series with said impedance circuits, and means operable under control of said relay system when a mutilated character signal is received for causing an error indicating character to be printed.

5 6. An arrangement in accordance with claim 4 and having three relays in said relay system, one of said relays being operable by the minimum current fed through one of said impedances, a second relay being operable whenever current is fed thereto simultaneously through at least the number of said impedances corresponding with the normal number of marking impulses in a code signal, and a third relay operable whenever current is fed thereto simultaneously through a number of said impedances in excess of the normal number of said marking impulses.

10 7. In a telegraph printer for equal length codes, means responsive to the reception of a mutilated signal having more or less than a predetermined unvarying number of marking impulses by which all the code signals are characterized for making an error indication, said means comprising a plurality of series-connected relays each operable 15 when fed with current of a predetermined amplitude and comprising further an error-designat-

ing type member operable when one only of said relays is, or all of the same are actuated, and means including a parallel arrangement of impedances in series with said relays and closable in accordance with the reception of marking impulses in each signal for determining the number of said relays to be actuated.

10 8. The method of automatically indicating a discrepancy between the transmission and reception of equal-length code signals, all of said signals as transmitted being characterized by an invariable number of marking elements differently disposed with respect to the spacing elements, which comprises producing a first response at the receiving station upon reception of the first marking impulse in each code signal, producing a second response which nullifies the effect of the first response whenever the number of received marking impulses in a signal is normal, and producing a third response which restores the effect 20 of the first response whenever the number of received marking impulses in a signal is excessive, and causing an error indication to result from the effects of either the first response or the third response.
